[57] CLAIM

The ornamental design for an automobile compass,
substantially as shown and described.

DESCRIPTION

FIG. 1 is a left front perspective view of an automobile
compass showing our new design;

FIG. 2 is a top plan view thereof;

FIG. 3 is a front elevational view thereof;

FIG. 4 is a right front perspective view thereof;

FIG. 5 is a rear elevational view thereof;

FIG. 6 is a bottom plan view thereof.

The broken line showings in FIGS. 1-4 are environmental
only, and form no part of the claimed design.
